(57) **CLAIM**

The ornamental design for "sidestick controller grip," as shown and described.

DESCRIPTION

This application which is related to commonly owned U.S. Utility application Ser. No. 13/305,721, filed Nov. 28, 2011, the entire content of such application being hereby expressly incorporated hereinto by reference.

FIG. 1 is a left-front perspective view of a left-handed sidestick controller grip showing our new design thereof,
FIG. 2 is a front elevational view thereof,
FIG. 3 is a rear elevational view thereof,
FIG. 4 is a right side elevational view thereof,
FIG. 5 is a left side elevational view thereof,
FIG. 6 is top plan view thereof,
FIG. 7 is a bottom plan view thereof,
FIG. 8 is a right-front perspective view of a right-handed sidestick controller grip showing our new design thereof,
FIG. 9 is a front elevational view thereof,
FIG. 10 is a rear elevational view thereof,
FIG. 11 is a right side elevational view thereof,
FIG. 12 is a left side elevational view thereof,
FIG. 13 is top plan view thereof; and,
FIG. 14 is a bottom plan view thereof.

The broken lines in FIGS. 1–14 represent structures in the environment of the claimed design, but which do not form part of the claimed design.

1 Claim, 14 Drawing Sheets
